UNITED STATES PATENT OFFICE

GLEN K. VAN EPPS, OF GRAND MOUND, IOWA, ASSIGNOR OF ONE-HALF TO HARRY MEINTS, OF GRAND MOUND, IOWA

BUCKET SUPPORT

Application filed July 16, 1928. Serial No. 293,021.

This invention relates to a milking bucket support, and more particularly to a bracket of novel construction attached to the bucket, and designed to not only support pivoted arms utilized to support the bucket from the knees of the user, but which bracket is also adapted to accommodate the usual bail.

More specifically stated the invention contemplates a bracket formed from a single blank of material bent upon itself to provide a U-shaped body portion to support a pair of pivoted arms for the purpose above mentioned, and also formed with an upstanding ear to accommodate the bail of the bucket, the component parts of the bracket being correlated to afford the bracket maximum strength and rigidity.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views and wherein:

Figure 1 is a view of a bucket showing the application of the invention.

Figure 2 is a perspective view of one of the brackets and pivoted arm.

Figure 3 is a vertical sectional view through one of the brackets showing the pivoted arm thereon.

Figure 4 is a plan view of the blank from which the bracket is formed.

Referring to the drawing in detail 10 represents a bucket of ordinary construction having the usual bail 11. Secured to the opposed sides of the bucket are brackets forming the subject matter of the present invention, and as illustrated in Figure 1 these brackets are designed to support a pair of pivoted arms employed to support the bucket from the knees of the user, and also to accommodate the bail 11.

Each bracket is formed from a single blank of material having a substantially T-shaped outline as clearly illustrated in Figure 4. The stem of the blank is bent along a transverse

line 12 at an appropriate point in its length, to form an ear, with the bent portions arranged in face to face contact as illustrated in Figure 2. The ear so formed is indicated at 13 and provided with an opening 14 to accommodate one end of the bail 11 as will be readily understood. The bent portions forming this ear are of relatively different lengths, the portion directly connected with the head of the T-shaped blank being the shortest, 60 the head being extended at a right angle to this particular portion of the stem to provide the horizontal portion 15 of a substantially U-shaped bracket, the head being bent downwardly along the lines 16 to provide the 65 opposed parallel portions 17 of the bracket. These parallel portions 17 are bent at right angles toward each other as at 18 and arranged to embrace the longer portion of the ear 13 as shown in Figure 2, these right angularly arranged extensions 18 being provided with openings 19 to accommodate suitable fastening elements for attaching the bracket to the bucket. The long branch or portion of the ear 13 is also provided with 70 similar openings 20 as shown in Figure 3 which registers with the openings 19. Curved arms 21 are pivoted between the parallel portions 17 of the brackets, and are arranged to be extended horizontally for use, the arms 80 being employed to support the bucket from the knees of the user in the well known manner. When extended for this use, the arms engage the under side of the cross piece 15 of the bracket as shown in Figure 3, and 85 when not in use the arms 21 assume positions at the sides of the bucket as indicated by dotted lines in Figure 1.

While it is believed that from the foregoing description the nature and advantages of the invention will be readily understood, I desire to have it known that I do not limit myself to what is herein shown and described and that such changes may be resorted to when desired as fall within the scope of what is 95 claimed.

What is claimed is:

1. A new and improved bracket formed from a single blank of material of substantially T-shape formation, the cross piece of 100

said blank bent to provide an inverted substantially U-shaped bracket, the stem of said blank being bent upon itself to provide an apertured bail receiving ear rising from said bracket, and an arm pivoted in the body portion of the bracket and adapted to be arranged horizontally for use.

2. A new and improved bracket formed from a single blank of material of substantially T-shape formation, the cross head of the blank being bent upon itself to provide an inverted substantially U-shaped bracket portion, an arm pivoted between the parallel portions of said bracket and adapted to be extended horizontally for use, the stem of said blank being bent upon itself to provide an apertured bail receiving ear rising from the bracket, and right angularly disposed extensions projecting from the parallel portions of the bracket and embracing the ear, said ear and right angular extensions having aligned openings for the purpose specified.

In testimony whereof I affix my signature.
GLEN K. VAN EPPS.
